John Staniford of Boston Mass.
Sellers Patent

The obverse referred to in these Letters Patent and making part of the same containing a description in the words of the said John Staniford himself of his improvement in the mode of manufacturing Essence Phials called the "tubular improvement".

To all to whom these presents shall come. I John Staniford of the City of Boston, in the County of Suffolk and Commonwealth of Massachusetts. Gifs Name and Noting.

Be it known that I the said John Staniford have invented, constructed, made and applied to use, a new and useful improvement in the mode of making or manufacturing, Glass Essence Phials, called the "tubular improvement", specified in the words and figures following.

The mode of making essence phials before the present improvement, and now generally in use is by taking the metal in a fluid state upon an iron pipe and blowing and forming as is usual in making phials and bottles of a larger size, to do which a party or second rod is necessary with fluid glass upon it which leaves the bottom rough when it is knocked off, and there is wasted, about one half the metal, the phials also are left rough, ill shaped unequal and imperfect from the impossibility of working so small a parcel of metal before it will cool. The improvement is as follows. I make the essence Phials from glass tubes prepared for the purpose of the size desired, I cut them into lengths sufficient for two Phials, then I work them by a large lamp and bellows blow pipe. I form the bungs at the ends of the tube with a pair of pincers and the necks with another pair of pincers, both of which pincers were ^{first} made and applied to this manufacture by me. The bungs and necks are made by applying the glass while the tube is heated in the lamp and by rolling the tube on a shifting inclined plane or form ground for the hand to

more or less planed, near the top, the lower end nose the other - this plan having been first made and applied to the nose by me - I then apply the heat to the middle of the tube and divide it, making the two bottoms to the same heat, and nearly at the same instant - the bottoms being made last are rendered perfectly smooth, (there being no party used) by the simple application of an iron to the part while heated. Another great advantage of this improvement is, that the Phials can be made much smaller, of uniform size, smooth straight, and beautiful, and the waste of metal instead of being one half, is only about one in two - And this new article can be supplied in any quantity desired with great rapidity, and at a rate at least as low as the old and imperfect kind can be either imported from Europe or manufactured in this country.

The drawings & references herewith exhibit - Fig 1. No 1. The glass tube as prepared for two Phials of a drachm each.

No 2. The end of the tube. - Fig 2. No 1. a tube with brims and necks formed and the formation of the bottoms commenced for two Phials of half drachm each. No 2. the end or brim. Fig 3. No 1. is a Phial in the finished state, of two drachms. No 2. the brim of the same. Fig 4. No. 1. is an open view of the pinces to form brims. No 2. is a side view of the same.

Fig 5. No. 1. Stop view of the inclined plane or form half size. No 2. Highest end of plane or form half size. No 3. side view of Plane or form half size. - Fig 6. No 1. pinces for forming the necks. No 2. & 3. End views of same.

In testimony that the above is a true specification of my said improvement as above described, I have here set my hand & seal this seventh day of September, in the year of our Lord Eighteen hundred and thirty one)
